UNITED STATES PATENT OFFICE.

PHILIP STERN, OF HARTFORD, CONNECTICUT, ASSIGNOR TO ROYAL TYPEWRITER COMPANY, OF NEW YORK, N. Y., A CORPORATION OF NEW JERSEY.

TYPE-WRITING MACHINE.

1,072,191.

Specification of Letters Patent.

Patented Sept. 2, 1913.

Application filed August 26, 1909. Serial No. 514,673.

To all whom it may concern:

Be it known that I, PHILIP STERN, a citizen of the United States of America, residing in Hartford, county of Hartford, and 5 State of Connecticut, have invented certain Improvements in Type-Writing Machines, of which the following is a specification.

This invention relates to a type bar slotted segment in which the type bars are pivoted.

10 In the accompanying drawings: Figure 1 is a front elevation: Fig. 2, a central transverse section: and Fig. 3, a similar section showing, however, an ordinary type bar guide adjacent the printing point and a type bar in printing position.

The segment 1 is cut with slots 2, for the reception of the pivot ends of the type bars 3 all pivoted upon a common pivot rod or wire 4 inserted in a segmentally curved 20 aperture or seat 5 formed in the segment. In the present construction, however, the seat or aperture 5 for the reception of the pivot wire 4 is formed in a novel manner. First, a slot 7 of uniform depth is cut, preferably in the curved lower or peripheral face 25 of the segment. The seat 5 for the reception of the pivot wire 4 has a greater diameter or width than the slot 7 and is cut by a tool having a cutting head of greater diameter than the width of the slot and a shank of such thickness as to freely pass 30 along the slot.

Fig. 2 shows the pivot wire seat or groove as square in cross section and in Fig. 3 it is indicated as round. To the segment is applied the usual vertically disposed type bar guide 8 below which is a segmental abut-

ment 9 against which the bodies of the type bars strike to prevent too deep an impression of their type faces into the paper being 40 printed on. The segment so formed with the pivot wire groove may, of course, be made of a single piece or casting.

I claim:

1. An integral type bar segment having a 45 radial web and a thickened rim formed with radial slots for type bar bearings, a segmental seat extending through the slotted part and a slot of less width than said seat extending therefrom to the exterior of the 50 rim, a single pivot rod disposed in said seat and extending across all the slots and, therefore, locked positively against lateral strains in all directions and type bars occupying the slots and turning about said rod. 55

2. An integral type bar segment having a rim enlarged in a forward direction and formed with radial slots open on three sides but closed at the back, a segmental pivot rod seat extending through the slotted part of 60 said rim and a segmental slot of less diameter than the seat extending therefrom to the exterior of the rim, a single pivot rod disposed in said seat across the slots and, therefore, locked positively against lateral 65 strains in all directions and type bars pivoted in the slots on said rod.

In testimony whereof, I have hereunto subscribed my name.

PHILIP STERN.
